(57) **CLAIM**

The ornamental design for a transcutaneous electrical nerve stimulation (TENS) device, as shown and described.

DESCRIPTION

FIG. 1 is a front perspective view of the transcutaneous electrical nerve stimulation (TENS) device;

FIG. 2 is a rear perspective view of the transcutaneous electrical nerve stimulation (TENS) device;

FIG. 3 is a front view of the transcutaneous electrical nerve stimulation (TENS) device, taken from the frame of reference of FIG. 1;

FIG. 4 is a rear view of the transcutaneous electrical nerve stimulation (TENS) device, taken from the frame of reference of FIG. 1;

FIG. 5 is a side view, in elevation, of the left side of the transcutaneous electrical nerve stimulation (TENS) device, taken from the frame of reference of FIG. 1;

FIG. 6 is a side view, in elevation, of the right side of the transcutaneous electrical nerve stimulation (TENS) device, taken from the frame of reference of FIG. 1;

FIG. 7 is an end view, in elevation, of the top end of transcutaneous electrical nerve stimulation (TENS) device, taken from the frame of reference of FIG. 1; and,

FIG. 8 is an end view, in elevation, of the bottom end of the transcutaneous electrical nerve stimulation (TENS) device, taken from the frame of reference of FIG. 1.

The broken lines are included for the purpose of illustrating unclaimed portions of the transcutaneous electrical nerve stimulation (TENS) device and form no part of the claimed design.
